Arthur M. Parker.

UNITED STATES PATENT OFFICE.

ARTHUR M. PARKER, OF LOS ANGELES, CALIFORNIA.

SEWING-AWL.

No. 909,817.

Specification of Letters Patent.

Patented Jan. 12, 1909.

Application filed September 21, 1908. Serial No. 454,093.

To all whom it may concern:

Be it known that I, ARTHUR M. PARKER, a citizen of the United States, residing at 415 Crocker street, Los Angeles, in the county of 5 Los Angeles and State of California, have invented a new and Improved Sewing-Awl, of which the following is a specification.

My invention is an improvement in the class of sewing-awls whose handles are provided with a recess or chamber to receive a 10 thread-wound spool, from which the thread passes to the awl-needle point and is drawn off as required.

The invention consists of novel features 15 and parts and combinations of same, as will be fully described hereinafter and pointed out in the claim.

A practical embodiment of the invention is represented in the accompanying drawings, forming a part of this specification, in 20 which similar characters of reference indicate corresponding parts in all the views.

Figure 1 is a perspective view of the sewing-awl; Fig. 2 is a sectional view of the 25 improvement showing the mounted spool C in the chamber B, the combination tension and spool locking-pin D, and retaining-peg F, the thread passage G, the chuck H, and the usual receptacle in the handle A for 30 the awl-needles and tools; Fig. 3 is a sectional view, at right angles with Fig. 2, showing the manner of mounting the spool C, and the end of the combination tension and spool locking-pin.

The improved sewing-awl is provided 35 with a suitable handle A, carrying at its front end a chuck H for receiving and holding a needle I of any approved construction. Extending into the side of the handle A is 40 arranged a chamber B, at its end a socket E for holding the end of the spindle J, on which the spool revolves. This spindle is used that the spool may be easier turned; but when the operator requires a friction be- 45 tween the walls of the chamber and the edges of the spool, that it may not allow the thread to easily leave the latter, the spindle is removed. As the thread K unwinds it leads

through the thread passage G, then along the handle to the eye of the awl-needle, as 50 indicated in the drawings.

The combination tension and spool locking-pin is slidably mounted in recess L, and when pressed in by the fingers of the operator, prevents the thread leaving the handle, 55 and thereby secures the thread with a firm grip, enabling the operator to draw the stitches tight without touching the thread. As the combination pin extends into and across the edge of the chamber B, it ob- 60 struct the chamber, and when the spool is within the chamber, it (spool) is prevented from leaving the chamber until the combination tension and spool locking-pin D is 65 drawn in the position indicated by the dotted lines M. The retaining peg F, prevents the locking-pin D from falling out of the handle.

By the novel features of construction and combination described, it will be seen that 70 the thread is not impeded in its passage through the thread passage, yet wholly under the control of the operator, and that the locking-pin D performs the functions of 75 tension and spool retainer.

Having thus described my invention, what I desire to secure by Letters Patent, is—

The combination with a sewing awl provided with a spool chamber, a thread passage leading therefrom to the outer surface 80 of the handle, and a recess extending from the thread passage to the outer surface of the handle, of a spool retainer or locking device slidably located in said recess and serving to retain the spool in its chamber 85 and act as a tension device for the thread by bearing upon the latter as it passes through the thread passage.

In testimony whereof I have signed my name to this specification in the presence of 90 two subscribing witnesses.

ARTHUR M. PARKER.
